Primary Examiner — Nicole C Shiflet*Assistant Examiner* — Karen M. Jones(74) *Attorney, Agent, or Firm* — Howard & Howard Attorneys PLLC(57) **CLAIM**

The ornamental design for an electronic smoking device, as shown and described.

DESCRIPTION

FIG. 1 is a top, right side perspective view of an electronic smoking device;

FIG. 2 is a bottom, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the electronic smoking device that form no part of the claimed design.

1 Claim, 3 Drawing Sheets(56)
